UNITED STATES PATENT OFFICE.

CHARLES F. L. KAUFMANN, CARL H. KAUFMANN, AND WALLER L. KAUFMANN, OF SANTA ANA, CALIFORNIA.

REGULATING DEVICE FOR SPOTLIGHTS.

Application filed April 13, 1921. Serial No. 461,042.

To all whom it may concern:

Be it known that we, CHARLES F. L. KAUFMANN, CARL H. KAUFMANN, and WALLER L. KAUFMANN, citizens of the United States, 5 residing at Santa Ana, in the county of Orange and State of California, have invented a new and useful Regulating Device for Spotlights, of which the following is a specification.

10 This invention relates to vehicle lamps and is particularly directed to that type of lamps known as "spotlights", the object of the invention being to provide an improved construction of adjustable mounting 15 by which the upward tilt of the lamp is limited when pointed directly ahead.

Another object is to provide a structure which will permit the lamp to be swung sidewise and tilted upwardly in a predetermined path, the progressive upward tilting coinciding in fixed relative ratio with the sidewise swing of the lamp producing a compound vertical and lateral circular adjustment of the lamp.

25 A further object is to provide means for varying the initial straight ahead adjustment of the lamp, and to provide an independent means for locking the adjustable means.

Various other objects and advantages will 30 be more fully apparent from the following description of the accompanying drawings which form a part of this disclosure, and which illustrate a preferred form of embodiment of the invention.

35 Of the drawings:

Figure 1 is a side elevation of the lamp in straight ahead position.

Fig. 2 is a front elevation showing the lamp swung sidewise and tilted upwardly.

40 Fig. 3 is an enlarged plan section on line x^3-x^3 of Fig. 1.

In a number of the States laws have been 45 passed regulating the use of spotlights and these laws require that the spotlight be so constructed that when in position to project its rays directly forward it cannot be tilted or moved vertically upward to such an extent that its rays will blind or confuse operators of vehicles or pedestrians facing the 50 lamp. The present improved spotlight is designed to comply with the law as to the straight ahead position of the lamp, but is also arranged so that should it be desired the lamp may be swung laterally and up-

wardly to illuminate road signs and for other purposes.

In the present invention the device is so arranged that in swinging the lamp sidewise it is tilted upwardly in a predetermined path with the upward tilting movement being in fixed ratio to the sidewise swing producing a compound vertical and lateral adjustment of the lamp from or to the straight ahead position.

In the drawings, 1 designates the upright standard of a vehicle windshield and 2 designates a spotlight bracket detachably secured thereto. Said bracket has an arm 3 provided at its free end with a horizontal stud 4 and a shoulder 5 at the base of the stud. A lamp supporting member 6 is pivoted on the stud 4 for vertical adjustment and is horizontally split outwardly from the stud to provide opposed limbs which are drawn together by a screw 7 to grip the stud sufficiently to frictionally maintain the member 6 in adjusted position against the vibration of the vehicle. This member 6 is, however, sufficiently loose on the stud 4 to permit a manual adjustment thereof, but when desired, it may be rigidly clamped in adjusted position by the screw 7. A nut 8 which engages the threaded end of the stud 4 maintains the member 6 on the stud 4.

The member 6 has a vertical bore 9 positioned outwardly from the stud 4 and adapted to receive the post 10 of the lamp 11. The free end of the member 6 is vertically split outwardly from the bore 9 and the opposed limbs so formed are drawn together by a screw 12 to frictionally clamp the post to maintain the lamp in adjusted position against the vibration of the vehicle.

The post 9 of the lamp is fixed to turn with the lamp and is slightly angled relative to the transverse plane of the lamp.

In use, with the lamp pointed straight ahead, the member 6 is vertically adjusted so that the lamp projects its rays to strike the road at the proper distance ahead of the vehicle, and this adjustment will by reason of the angularly disposed lamp post 10, cause the member 6 to be angularly disposed relative to the horizontal. With the lamp in such position (see Fig. 1) any sidewise swing of the lamp will cause the lamp to tilt upwards in a fixed ratio so that the degree of tilt will increase in direct propor-

tion to the degree of such sidewise swing, (see Fig. 2), such proportion being dependent upon the degree of the angle of the post 10 relative to the transverse plane of the 5 lamp.

In its preferred form the post 10 is so angled relative to the lamp that when the lamp is swung sidewise it will be tilted upwardly to the proper angle to project the 10 light to the height of the standard road signs and by reason of this the lamp can be turned to illuminate such signs without disturbing the initial adjustments and can then be positively returned to proper straight 15 ahead position. The specific embodiment of the invention illustrated in the drawings, while well adapted for the purposes primarily stated, is susceptible of various changes and modifications without departing 20 from the broad scope of the following claims.

We claim:

1. In a device of the class described, a supporting bracket, and a lamp having a 25 supporting post disposed in a vertical plane intersecting the axis of the lamp and angled rearwardly relative to the transverse plane of the lamp, said post being journaled in the bracket, whereby the lamp will tilt upwardly when swung laterally in either direction from a normal straight ahead position.

2. In a device of the class described, a bracket, a lamp supporting member pivoted 35 on the bracket to swing vertically, a lamp having a post disposed in a vertical plane intersecting the axis of the lamp and angled relative to the transverse plane of the lamp and vertically journaled in said member.

3. In a device of the class described, a bracket having a horizontal stud, a lamp supporting member journaled on said stud and having an aperture disposed in a plane 40 at right angles to said stud, a lamp having a post disposed in a vertical plane intersecting the axis of the lamp and angled relative 45

to the transverse plane of the lamp and engaging in said aperture, means for frictionally clamping the member on the stud, and means for frictionally clamping the 50 post.

4. In a device of the class described, a bracket, a lamp, and an intermediate angled lamp supporting post vertically aligned with the longitudinal axis of the lamp and 55 permitting a swinging of the lamp relative to the bracket, the angled disposition of said post compelling a compound lateral swing and upward tilting of the lamp when the lamp is swung in either direction from a 60 normal straight ahead position.

5. In a device of the class described, a bracket having a lateral stud, a lamp supporting member having a horizontal aperture through which said stud engages and 65 a vertical aperture, a lamp having a post disposed in a vertical plane intersecting the axis of the lamp and angled relative to the transverse plane of the lamp and engaging in the vertical aperture of the lamp supporting member, said member being horizontally split outwardly from the horizontal aperture and vertically split outwardly from the vertical aperture forming opposed limbs at opposite ends of said member, means 70 drawing the one pair of limbs together to clamp the member on the stud, means drawing the other pair of limbs together to clamp the lamp post on said member.

6. In the construction defined in claim 5, 80 the bracket having a shoulder at the base of the stud, and independent means, maintaining the lamp supporting member against said shoulder.

Signed at Santa Ana, California, this 4th 85 day of April, 1921.

CHARLES F. L. KAUFMANN.
CARL H. KAUFMANN.
WALLER L. KAUFMANN.
